UNITED STATES PATENT OFFICE.

VINCENT CECI, OF NEW YORK, N. Y., ASSIGNOR TO SCHMIDT-DAUBER CO., INC., OF NEW YORK, N. Y., A CORPORATION OF NEW YORK.

ILLUMINATING MEANS FOR PLAYER PIANOS AND THE LIKE.

Application filed August 8, 1924. Serial No. 730,814.

To all whom it may concern:

Be it known that I, VINCENT CECI, a citizen of the United States, and a resident of the borough of Queens, Queens County, city 5 and State of New York, have invented an Improvement in Illuminating Means for Player Pianos and the like, of which the following is a specification.

My present invention relates to control 10 means for electrical adjuncts or accessories, such as illuminating means for mechanical musical instruments, especially music-roll operated mechanical musical instruments, such as player pianos and 15 the like, and aims to provide means of the general character specified above which are simple in construction, easy, compact and economical to install with little alteration in the construction and arrangement of 20 parts of the instruments to which the means of the present invention are applied, which are certain and safe in operation, and in which the electrical appliance, such as an electric lamp for illuminating a music well 25 or other compartment in which the music roll may be positioned, shall be automatically controlled by the insertion and removal of the music roll, the insertion of the music roll acting to turn on or render operative 30 the electric lamp or other electrical appliance, and the removal of the music roll acting to turn off or render inoperative the electric lamp or other electrical appliance, or vice versa, depending upon the particular 35 electrical appliance employed and the results desired to be obtained.

In the accompanying specification I shall describe, and in the annexed drawing show, one illustrative embodiment of the apparatus of the present invention. It is, however, to be clearly understood that my invention is not limited to the specific form thereof herein shown and described for purposes of example merely.

Referring to the drawing, wherein I have illustrated the aforesaid illustrative embodiment of the apparatus of the present invention:

Fig. 1 is a view in front elevation, partly 50 in section and partly broken away, showing the aforesaid illustrative embodiment of the device of the present invention, with the music roll removed and the switch, controlling the lamp for illuminating the music well or like compartment in which the music

roll is normally positioned, in the open or "off" position; and

Fig. 2 is a detailed view, on an enlarged scale, of the switch-operating mechanism of Fig. 1 with the music roll in place to be 60 played upon and with the switch in closed or "on" position.

Referring now more particularly to the aforesaid illustrative embodiment of the present invention and especially to the drawing illustrating the same, 10 indicates a music well or like compartment of a player piano or other mechanical musical instrument adapted to be operated by a music roll or the like, here generally indicated by reference character P. The music well or like compartment 10, which is adapted to receive the player or music roll 11, is defined by means of a frame 12 which generally has the form shown more clearly in Fig. 1 of the drawing. As shown, the lower portion of the frame 12, defined by the side members 13 and 14 and the bottom portion 15, is substantially rectangular, while the upper member 16 is arcuate or rounded. 70

Extending into the upper or music roll compartment 17 of the well 10 is the non-reciprocable spindle 18 generally connected to a portion of the driving mechanism for the music roll 11. Likewise extending into the upper portion 17 of the well 10 is the reciprocable spindle 19 slidably mounted in a suitable bearing 20 mounted in the side 13 of the frame 12. 21 indicates the tracker bar provided with the usual openings 22 and defining below it the space 23 for the winding spool 24 mounted in the usual manner and driven by a portion of the driving mechanism of the player piano or like music-roll operated mechanical musical instrument. 80

At 25 I have indicated the electrical adjunct or accessory adapted to be controlled and operated by means of the present invention, and comprising in this case an electric lamp extending into the upper portion 17 of the music well 10 adjacent the top of the same. The lamp 25 is so positioned that it will throw the required degree of illumination upon the music roll 11 when the same is being played, especially where such music roll is of the "word" variety, that is, of the type where the words of the song being played by the player piano or other mechanical musical instrument are printed on the roll synchronously with the

110

music cut therein, so that persons may sing the words while the instrument plays an accompaniment. It will be noted that the arcuate form of the upper member 16 of the frame 12 permits the electric lamp 25 or its equivalent to be positioned so as to effectively illuminate the roll 10 but without in any way interfering with the operation of the roll or cutting into the space required for its insertion and removal.

In order that the electric lamp 25 may give the desired lighting effect and at the same time be artistically pleasing, I may provide the inner surface 16' of the arcuate member 16 with an arcuate reflector 26, and may also provide the electric lamp 25 with a translucent or transparent arcuate shade 27 of any desired color or quality of glass or other vitreous or like substance, in order to give a light which is at once suitable for the desired purpose and pleasing to the eye. The lamp 25 is screwed into a socket 28 mounted on an insulating or other suitable base 29 carried by the arcuate wall 16 of the frame 12. 30 and 31 indicate the leads or connectors passing from the lamp contacts 30' and 31' to the snap switch or like electrical controlling means, here generally indicated by reference character 32 and shortly to be described in greater detail herein.

The switch 32 is preferably of the "two-way" snap type, that is, both opening and closing by a snap action. Preferably the operation of the switch 32, into and out of closed position, is effected by the reciprocating movement of a switch-operating member, here generally indicated at reference character 33. The switch itself may be carried by the arm or bracket 34 attached, as by means of the screws or other fastening members 35, to a block 36 carried by the outer face 18' of the side 13 of the frame 12. The contacts 30 and 31 are connected to the switch 32 in the manner which will be well known to those skilled in the art to which the present invention relates. It will also be noted that the switch-operating member 33 is provided with the switch-operating spindle 33', whereby the reciprocation of the switch-operating member 33 through the spindle 33' will, in one direction of its movement, to the left in Figs. 1 and 2 of the drawing, close the switch, and in the other direction of its movement, to the right in Figs. 1 and 2 of the drawing, open the switch.

Referring now more particularly to Fig. 2 of the drawing, the reciprocable spindle 19 is provided at its inner end, which is the end which extends into the music well 10, with the roll-engaging portion 35 and at its other end, comprising a portion 36 of reduced cross-section, with the enlarged button-shaped projection 37 adapted to engage

the inner end 33" of the switch-operating member 33 for the operation of the switch 32. Mounted within the bearing or housing 20, which preferably has the form shown more clearly in Fig. 2 of the drawing, is a compression spring 38 which bears at one end against the inner end 39 of the housing 20 and at its other end against the inner end 40 of that portion of the spindle 19 which is of the larger cross-section. It will thus be noted that the compression spring 38 tends to maintain the reciprocable spindle 19 in forward position extending as far as possible into the music well 10.

The inner movement of the reciprocable spindle 19 is determined by the engagement of the enlarged or button-shaped inner end 37 of the portion 36 of reduced cross-sectional area with the inner arm 41 of the connecting member 42, the upper arm 43 of which is fixedly attached to the operating member 33 of the switch 32. For this purpose the inner portion 36 of reduced cross-sectional area passes through the opening 44 in the inner arm 41 of the connecting member 42. In order to render the operation of the switch and its associated parts as noiseless as possible, I prefer to provide the inner face 37' of the enlarged portion 37 with a strip of felt or like sound-deadening material 45, and the outer face 37" of the enlarged portion 37 with a strip of felt 46.

In order to provide for the proper operation of the switch in the control of the electric lamp 25 or other electrical accessory, it is necessary to so space and arrange the various members 36, 42 and 33, that upon the insertion of a music roll 11 so that the inner end 11' will engage the non-reciprocable spindle 18 and the outer end 11" will engage the inner end of the reciprocable spindle 19, the movement of the spindle 19 to the left in Figs. 1 and 2 of the drawing, necessitated by the insertion of the music roll 11, will cause the inner end 36 of the spindle 19 and the enlarged member 37 carried thereby to engage the switch-operating member 33 to close the switch. Upon the insertion of the roll, as will be clear to those skilled in the art to which the present invention relates, there will be a slight reverse movement of the spindle 19, under the action of the compression spring 38, to enable the same to enter the orifice with which the outer end 11" of the music roll 11 is generally provided. There should, accordingly, be enough lost motion or free play between the reciprocable spindle 19 and the connecting member 42, which latter is fixedly attached to the switch-operating member 33, to permit this reverse travel of the spindle 19 without causing the spindle on its reverse movement to operate the connecting member 42 to open the switch again. It is only when the music roll 11 is removed that the spindle 19

completes this reverse movement to the right, as shown in Figs. 1 and 2 of the drawing, to actuate the operating member 42 to operate upon the switch-operating member 5 to open the switch.

The movement of the spindle 19, the connecting member 42, and the switch-operating member 33, to close the switch, takes place against the action of the compression spring 38, while the movement of these three members in the reverse direction upon the removal of the roll to open the switch, takes place under the action of the compression spring 38.

15 It will thus be seen that the insertion of the roll acts in a simple, direct and certain manner to close the switch to turn on the illuminating device 25, thus lighting up the music roll compartment while the roll is being played, while the removal of the roll causes the illuminating means to be turned off when its use is no longer required. This action takes place automatically and by means which are simple in construction, 20 easy, compact and economical to install, and certain and safe in operation. It may here be stated that in place of the usual lighting circuit, storage or even primary batteries 25 may be used as the source of power for energizing the lamp or other electrical appliance arranged in accordance with the principles 30 of the present invention.

What I claim as my invention is:

1. In a music-roll operated mechanical 35 musical instrument, such as a player-piano or the like, a roll-receiving compartment, a roll-supporting spindle reciprocably mounted with its outer end extending into said compartment, an electric switch provided 40 with an operating member adapted to be actuated by said spindle, and spring means normally acting to maintain said spindle in forward position and said switch in open position.

45 2. In a music-roll operated mechanical musical instrument, such as a player-piano or the like, a roll-receiving compartment, a roll-supporting spindle reciprocably mounted with its outer end extending into said 50 compartment, an electric switch provided with an operating member adapted to be actuated by said spindle, means connecting said spindle and said operating member, and spring means normally acting to maintain 55 said spindle and said connecting means in forward position and said switch in open position.

60 3. In a music-roll operated mechanical musical instrument, such as a player-piano or the like, a roll-receiving compartment, a roll-supporting spindle reciprocably mounted with its outer end extending into said compartment, an electric switch provided 65 with an operating member adapted to be actuated by said spindle, and spring means

normally acting to maintain said spindle in forward position and said switch in open position, said spindle being adapted, upon the insertion of a music roll, to actuate said operating member to bring said switch into 70 closed position.

4. In a music-roll operated mechanical musical instrument, such as a player-piano or the like, a roll-receiving compartment, a roll-supporting spindle reciprocably mounted 75 with its outer end extending into said compartment, an electric switch provided with an operating member adapted to be actuated by said spindle, means connecting said spindle and said operating member, 80 and spring means normally acting to maintain said spindle and said connecting means in forward position and said switch in open position, said spindle being adapted, upon the insertion of a music roll, to actuate said operating member to bring said switch into 85 closed position.

5. In a music-roll operated mechanical musical instrument, such as a player-piano or the like, a reciprocable roll-supporting 90 spindle having a roll-supporting outer end and a switch-engaging inner end, an electric switch having an operating member adapted to be engaged by the inner end of said spindle, and means normally tending 95 to maintain the inner end of said spindle in non-engaging position with respect to said switch-operating member.

6. In a music-roll operated mechanical musical instrument, such as a player-piano 100 or the like, a reciprocable roll-supporting spindle having a roll-supporting outer end and a switch-engaging inner end, an electric switch having an operating member adapted 105 to be engaged by the inner end of said spindle, and spring means normally tending to maintain the inner end of said spindle in non-engaging position with respect to said switch-operating member, the insertion 110 of a music roll causing the inner end of said spindle to bear against said switch-operating member against the action of said spring means to close said switch.

7. In a music-roll operated mechanical musical instrument, such as a player-piano 115 or the like, a reciprocable roll-supporting spindle having a roll-supporting outer end and a switch-engaging inner end, and an electric switch having an operating member adapted to be engaged by the inner end of 120 said spindle, in combination with means attached to said switch-operating member and slidably engaging the inner end of said spindle for actuating said switch-operating member to open said switch upon the removal of said music roll.

8. In a music-roll operated mechanical musical instrument, such as a player-piano 125 or the like, a reciprocable roll-supporting spindle having a roll-supporting outer end 130

and a switch-engaging inner end, an electric switch having an operating member adapted to be engaged by the inner end of said spindle, and means normally tending to maintain the inner end of said spindle in non-engaging position with respect to said switch-operating member, in combination with means attached to said switch-operating member and slidably engaging the inner end of said spindle for actuating said switch-operating member to open said switch upon the removal of said music roll.

9. In a music-roll operated mechanical musical instrument, such as a player-piano or the like, a reciprocal roll-supporting spindle having a roll-supporting outer end and a switch-engaging inner end, an electric switch having an operating member adapted to be engaged by the inner end of said spindle, and spring means normally tending to maintain the inner end of said spindle in non-engaging position with respect to said switch-operating member, the insertion of a music roll causing the inner end of said spindle to bear against said switch-operating member against the action of said spring means to close said switch, in combination with means attached to said switch-operating member and slidably engaging the inner end of said spindle for actuating said switch-operating member to open said switch under the action of said spring means upon the removal of said music roll.

10. In a music-roll operated mechanical musical instrument, such as a player-piano or the like, a reciprocal roll-supporting spindle, spring means for yieldingly pressing said spindle into roll-engaging position, a switch provided with a switch-operating member, and means associated with said switch-operating member and said spindle for closing said switch upon the insertion of a music roll and for opening said switch upon the removal of said music roll.

45 11. In a music-roll operated mechanical musical instrument, such as a player-piano or the like, a reciprocal roll-supporting spindle, spring means for yieldingly pressing said spindle into roll-engaging position, a switch provided with a switch-operating member, and means associated with the outer end of said switch-operating member and the inner end of said spindle for closing said switch against the action of said spring upon the insertion of a music roll and for opening said switch under the action of said spring upon the removal of said music roll.

60 12. In a music-roll operated mechanical musical instrument, such as a player-piano or the like, a music well for containing a music roll, a reciprocal roll-supporting spindle extending into said music well,

spring means for yieldingly pressing said spindle into roll-engaging position, a switch provided with a switch-operating member, an electric lamp within said music well and controlled by said switch, and means associated with said switch-operating member and said spindle for closing said switch upon the insertion of a music roll and for opening said switch upon the removal of said music roll.

13. In a music-roll operated mechanical musical instrument, such as a player-piano or the like, a music well for containing a music roll, a reciprocal roll-supporting spindle extending into said music well, spring means for yieldingly pressing said spindle into roll-engaging position, a switch provided with a switch-operating member, an electric lamp within said music well and controlled by said switch, and means associated with the outer end of said switch-operating member and the inner end of said spindle for closing said switch against the action of said spring upon the insertion of a music roll and for opening said switch under the action of said spring upon the removal of said music roll.

14. In a music-roll operated mechanical musical instrument, such as a player-piano or the like, a reciprocal roll-supporting spindle, spring means for yieldingly pressing said spindle into roll-engaging position, a switch provided with a switch-operating member, and means comprising a connecting member attached to the outer end of said switch-operating member and having sliding engagement with the inner end of said spindle for closing said switch upon the insertion of a music roll and for opening said switch upon the removal of said music roll.

15. In a music-roll operated mechanical musical instrument, such as a player-piano or the like, a music well for containing a music roll, a reciprocal roll-supporting spindle extending into said music well, spring means for yieldingly pressing said spindle into roll-engaging position, a switch provided with a switch-operating member, an electric lamp within said music well and controlled by said switch, and means comprising a connecting member attached to the outer end of said switch-operating member and having sliding engagement with the inner end of said spindle for closing said switch upon the insertion of a music roll and for opening said switch upon the removal of said music roll.

In testimony, whereof, I have signed my name to this specification this 10th day of July, 1924.

VINCENT CECI.
